INKING MECHANISM FOR PRINTING MACHINES

Frederick Lamatsch, Grantwood, N. J., assignor,
by mesne assignments, to R. Hoe & Co., Inc.,
New York, N. Y., a corporation of New York

Application October 23, 1934, Serial No. 749,637

18 Claims. (Cl. 101—350)

This invention relates to printing machines, and more particularly to certain improvements in inking mechanism for high speed rotary printing presses.

Engineers in the designs of modern high speed rotary printing presses are constantly faced with the problem of providing improved means for satisfying the progressively increasing demand for greater printing speed and space conservation, and also for the production of higher quality printing. In printing presses of the newspaper type, the modern tendency is to condense the printing units as far as possible, consistent with good printing, and in these units the inking mechanism is usually positioned below the printing cylinders. The inking mechanism, in conformity with the demand for space conservation, is also condensed as far as possible without sacrificing printing quality. Many experiments have been resorted to to solve this problem, but it has been found that the employment of rotary reciprocating ink distributing cylinders best satisfy the design requirements for good quality printing in this type of printing machine. In order that high grade printing may be produced, it is necessary that the supplied ink be first worked into a uniform ink film, and then conveyed to the printing surface or printing plate of the plate cylinders. If a great number of ink distributing cylinders and rollers are employed, satisfactory results may be produced, but owing to the requirements for condensed printing units, the number of operating components employed, such as ink distributing cylinders and rollers, is necessarily limited.

Inking mechanism has been provided in which two rotary reciprocating ink distributing cylinders are employed, but such an arrangement is not entirely satisfactory owing to the tendency of varying torque being set up in the cylinder driving mechanism. The two cylinder arrangement is further objectionable, because, at times, only one cylinder is being reciprocated, and the axially stationary cylinder tends to produce unequal distribution of ink supplied to the surface of the printing cylinders. This objection could be overcome by employing a greater number of ink distributing cylinders, but such an arrangement would be impractical, owing to the space required for their utilization. The employment of any number of ink distributing cylinders greater than three or four is not practically feasible in the modern high speed rotary printing presses, because their use would increase the

size of the printing units to objectionable proportions.

Applicant has found that novel and unexpected results are obtained by employing three ink distributing cylinders in the inking mechanism of each printing couple of modern high speed printing presses, and an object of the present invention is to provide an ink mechanism for high speed rotary printing presses in which the essential operating components of the inking mechanism are constructed and arranged to supply a uniform ink film to the printing surface or plate of each plate or form cylinder with the employment of a minimum number of operating components and preferably three rotary reciprocating ink distributing cylinders.

Another object of this invention is to provide an inking mechanism for rotary printing machines, in which a plurality of rotary ink distributing cylinders are employed, and these cylinders so operated that each cylinder is reciprocated axially in a uniform period of a complete cycle of operation of all the cylinders, and only one cylinder being axially stationary at a time.

A further object of this invention is to provide an inking mechanism for rotary printing machines, in which three inking distributing cylinders are employed for each plate cylinder of the printing machine, and these cylinders reciprocated by a common rotary instrumentality so that uniform torque is set up in the driving instrumentality, and each cylinder reciprocated during a uniform period of a complete operating cycle of all the cylinders.

A more specific object of this invention is to provide an inking mechanism for each plate cylinder of a rotary printing machine, and each inking mechanism including three horizontally disposed ink distributing cylinders positioned in substantially vertical alignment immediately below each plate cylinder, and the supplied ink conveyed to the lowermost ink distributing cylinder at a portion of its periphery which is disposed toward the center of the machine.

Another object of this invention is to provide an inking mechanism for rotary printing machines in which three ink distributing cylinders are employed for each plate cylinder, and these cylinders driven by a common instrumentality so that each cylinder is reciprocated 120 degrees in advance of the succeeding or following cylinder in the sequence of operation of these cylinders.

An additional object of this invention is to provide a printing machine including a plurality of mechanical connections for imparting drive

- impulses to the operating components of the printing machine, and an oil tight housing containing lubricant for each mechanical connection and constructed and arranged so that each housing is entirely independent of the remaining housings.

It is also an object of my present invention to provide for use in printing machines an inking mechanism of generally improved construction and arrangement, whereby the device will be simple, durable and inexpensive in construction, as well as convenient, practical, serviceable and efficient in its use.

With the foregoing and other objects in view, which will appear as the description proceeds, the invention resides in the combination and arrangement of parts, and in the details of construction hereinafter described and claimed, it being understood that various changes in form, proportion, and minor details of construction may be made within the scope of the claims without departing from the spirit or sacrificing any advantages of the invention.

For a complete disclosure of the invention, a detail description of a printing machine embodying the improved inking mechanism will now be given in connection with the accompanying drawings forming a part of this specification, wherein:—

30 Figure 1 is an elevational view of a printing unit, looking in the direction of the axes of the printing cylinders and showing the improved inking mechanism applied thereto;

35 Figure 2 is a fragmental side elevation of the printing unit depicted in Figure 1, and viewed in the direction of the indicated arrow, parts being shown in the sections; and

40 Figures 3, 4, 5 and 6 are diagrammatical views depicting phases of operations of the improved inking mechanism.

Referring to the drawings, in which similar reference characters designate corresponding parts, 10 and 11 indicate the side frames of a printing unit in which the two printing couples A and B are operably mounted. Each printing couple includes a plate or form cylinder 14 and an impression cylinder 15. Any suitable means may be employed for driving the printing couples, and in the present instance, in conformity with the usual practice, a vertical shaft 17 is driven from any operating component, not shown, of the printing machine, and this shaft carries a beveled pinion 18 which meshes with a beveled gear 19, and the gear 19 is secured to and rotates with a gear 20, which, in turn, meshes with a gear 21 secured to the shaft or trunnion 22 of the impression cylinder 15 of the printing couple A. The shaft or trunnion 23 of the cylinder 14 of the printing couple A has a gear 24 secured thereto, and the gear 24 meshes with the gear 21, thereby completing the drive for the printing couple A. The printing couple B is also driven from the vertical shaft 17 through a gear 26, which meshes with the gear 20. The gear 26 is operably supported by the shaft or trunnion 23 of the plate cylinder 14 of the printing couple B, and the gear 26 meshes with a similar gear 28 carried by the shaft 22 of the impression cylinder 15 of the printing couple B.

70 By this arrangement the printing cylinders are driven in operable synchronism, but it is to be understood that any preferred form of cylinder drive may be resorted to and that this drive forms no part of the present invention.

75 The web W is led from any suitable web sup-

ply, not shown, over a roller 30 to the first printing couple A, and then over a roller 31 to the second printing couple B, where the web is perfected, in conformity with the usual practice.

The improved inking mechanism forming the subject matter of this application, includes three horizontally disposed ink distribution cylinders 34 for each plate cylinder of the printing unit. Inasmuch as the inking mechanism for each plate cylinder is similarly constructed and arranged, only one of the inking mechanisms will be described in detail in order that repetition may be avoided.

The shaft or trunnion of each plate cylinder 14 has a drive worm 36 secured to one terminal thereof, and this worm meshes with a worm wheel 37, carried by a substantially vertically disposed crank shaft 39. The upper portion of the crank shaft 39 is rotatably mounted in a bearing 40 formed in a cap or removable portions 42 of an oil or lubricant container or housing 43 which incloses the worm 36, worm wheel 37 and gear 24. The crank shaft 39 is also rotatably mounted in spaced bearings 44 formed in or supported by separate oil or lubricant receptacles or housings 46, the purpose of which is to be hereinafter disclosed. Each ink distributing cylinder 34 is provided with a shaft or trunnion 48, and each shaft is mounted for both rotation and reciprocation in bearing members 50, supported by the machine frames 10 and 11. The end of each ink distributing cylinder shaft 48 which is positioned towards the crank shaft 39 is provided with a swivel-head 52. Each swivel-head 52 is provided with spaced lugs or bearing ears 54, to which a connecting rod or pitman 56 is pivotally secured, and the opposed terminal of each pitman 56 is operably secured to an offset portion or crank member 58 carried by the crank shaft 39. The detailed construction of the swivel-heads 52, connecting rods 56 and crank members 58 is disclosed in United States Patent No. 1,977,444.

In order that ready access may be had to each lubricating receptacle or housing 46, there is provided a detachable cover member or closure 60 for each housing, and each cover member is secured to its housing by suitable securing devices 62. Each crank shaft 39 is held against longitudinal motion at one terminal by a collar or sleeve 38, formed on the worm gear 37 and engaging the inner face of the bearing 40 of the lubricant housing 42, and the opposed terminal of the crank shaft 39 is held against longitudinal motion by a collar or washer 64 and a screw or suitable securing device 66. In order to prevent the escape of lubricant from the lowermost lubricant housing 46 through its lower bearing 44, an oil seal or member 68 surrounds the collar and securing members 64 and 66.

The crank mechanism imparts reciprocatory motion to the ink distributing cylinders 34, as will be hereinafter more fully disclosed, and in order to rotate these cylinders a suitable gear train is provided, as disclosed in United States Patent No. 1,977,444. This gear train includes gears 70, secured to the terminals of the ink distributor cylinder shafts 48, and the gears 70 mesh with broad idler gears 72, and the uppermost of the idler gears 72 is driven from gear 74 which is operably supported by the shaft 23 of each printing cylinder 14.

The ink distributing cylinders, as disclosed in Figures 1 and 2, are horizontally disposed and arranged so that they are positioned in substantially vertical alignment below each plate cylinder. 75

By this arrangement a compact structure is produced and one which peculiarly lends itself to advantageous positioning of the ink supplying rails. As shown in Figure 1, form rollers 76 operably engage the uppermost ink distributing cylinder 34, and the adjacent plate cylinder 14. Ink distributing or transfer rollers 78 are operably interposed between the adjacent ink distributing cylinders 34, and the peripheral portions of the 5 rollers 78 engage the peripheries of these ink distributing cylinders. Additional ink distributing rollers 80 are also positioned to engage the peripheral portions of the ink distributing cylinders 34 which are positioned towards the center of the 10 printing unit, thereby further aiding in producing a uniform ink film.

By this arrangement the three ink distributing cylinders 34 for each plate cylinder 14 are driven so that the portions of their peripheries which are 15 positioned toward the center of the printing unit move or rotate upwardly, and the upwardly moving portion of the peripheries of each lowermost ink distributing cylinder has ink supplied thereto by an ink rail 82. This arrangement permits each 20 ink rail to be positioned at a point furthest removed operably from each plate cylinder, and, also, permits the ink rails to be positioned towards the central portion of the printing unit between the inking mechanisms. This construction and 25 arrangement is highly advantageous, because each ink rail 82 is positioned at a point most remote operably from the plate cylinders thereby insuring perfect ink distribution; and these ink rails are also located at points removed from the 30 aisle space provided at each side of the printing machine, thus affording the machine operator ready access to these aisle spaces. In compliance with the demand for space conservation, the printing units of a modern printing line are 35 placed as closely together as is possible consistent with the ready access of the operators into the aisle space provided between adjacent units. Therefore, applicant, by providing a construction and arrangement which locates ink rails between 40 the ink distributing mechanisms and away from the aisle space does thereby conserve valuable 45 aisle space.

Each crank shaft 39 has its offset or crank portions 58 arranged 120 degrees apart, as disclosed in Figures 3, 4, 5 and 6, and inasmuch as three crank members are provided for each crank shaft a complete rotation of 360 degrees of the crank shaft imparts a complete reciprocatory cycle of operation to the three ink distributing 50 cylinders operated by the crank shaft. By this arrangement, substantially constant torque is insured during the operation of the crank shaft 39, and no more than one ink distributing cylinder 34 is axially stationary at a given time, thus insuring 55 perfect ink distribution. These advantages are peculiarly existent in an arrangement where three crank members are carried by a common shaft or rotating member, because, if only two cranks were employed and they are uniformly spaced, 60 then both their ink distributing cylinders would be stationary at the same time. If an attempt were made to avoid both cylinders being stationary at the same time by positioning the crank members so that they are spaced more or less than 180 65 degrees apart, then the operating torque would be unequally distributed, thereby setting up objectionable vibratory impulses. If four cylinders and four crank members were employed, then two of the cylinders would be stationary at a time, which 70 tends to produce faulty ink distribution, and the 75

employment of any number of cylinders greater than four would be practically impossible owing to the space limitation in the design of modern high speed printing machinery.

The operation of the three ink distributing cylinders by a common crank shaft is diagrammatically depicted in Figures 3, 4, 5 and 6, and the relative operable positions of the three cranks 58 are indicated at 58', 58² and 58³ in these figures. Referring to Figure 3, 58' indicates the relative 10 position of one of the ink distributing cylinder operating cranks where the crank has arrived at a point of minimum load, and the axial movement of its ink distributing cylinder 34 has, for an instant, ceased. In this position, the remaining 15 two crank members are positioned at their points of intermediate load, indicated at 58² and 58³, where intermediate reciprocatory speed is imparted to their ink distributing cylinders 34, but in opposite directions. Thus it is seen, that in 20 this position the intermediate load of the two crank members 58² and 58³ balances the zero load of the crank member 58', and the axial movement at intermediate speed of two of the ink distributing cylinders in opposite directions 25 neutralizes the effect of the stationary cylinder.

After the cranks have moved clockwise a short distance, the crank member 58³ arrives at its point of maximum load, as indicated in full lines in Figure 4, where it imparts maximum reciprocatory speed to its ink distributing cylinder 34. In this position the crank member 58' has arrived at a point of intermediate load, where it imparts intermediate axial speed to its ink distributing cylinder, and the member 58² has nearly reached 30 the point of zero load, where it, in turn, is imparting almost zero axial speed to its distributing cylinder. The position of intermediate load of crank member 58' and the almost zero load of the crank member 58², compensates for the maximum 35 load of the crank member 58³, thereby insuring substantially constant torque; the intermediate and practically zero speed imparted to two of the ink distributing cylinders by their crank members 58' and 58² while the remaining cylinder is being 40 reciprocated at maximum speed by its crank 58³ insures perfect ink distribution during this phase 45 of the operation of the ink distributing mechanism.

Further rotation of the crank shaft 39 brings 50 the crank member 58² to its outer position of zero load, as shown in Figure 5, and the crank members 58' and 58³ are then located at positions of intermediate load. In this position the ink distributing cylinder 34 which is operated by the 55 crank member 58² is momentarily stationary, but the cylinders operated by the crank members 58' and 58³ are moving at intermediate reciprocatory speeds, but in opposite directions. Thus it is seen that the zero load of crank members 58² 60 is compensated by the intermediate load of the two crank members 58' and 58³, thereby insuring substantially constant torque. In this position the stationary position of the cylinder which is operated by the crank 58² is also compensated by 65 the cylinders which are operated by the cranks 58' and 58³ moving at intermediate axial speeds in opposed directions.

As shown in Figure 6, further clockwise movement of the crank shaft 39 positions the crank member 58' at its point of maximum load, where it also imparts maximum axial speed to its ink distributing cylinder. In this position the crank member 58² is at a position of almost zero load, and the crank member 58³ is positioned at a point 70 75

of intermediate load. Thus, the nearly zero load of crank member 58², and intermediate load of crank member 58³, neutralizes the maximum load of the crank member 58'. Also in this position, the almost zero axial speed of the ink distributing cylinder which is operated by the crank member 58², and the intermediate axial speed of the distributing cylinder which is operated by the crank member 58³ opposes the maximum axial reciprocatory speed which is imparted to the cylinder by the crank member 58'.

From the foregoing, it is manifest that by providing an inking mechanism incorporating three rotary ink distributing cylinders which are axially reciprocated or "vibrated" by three crank members spaced 120 degrees apart, that no more than one cylinder is ever stationary at a time, and, consequently, two cylinders are constantly moving axially to insure perfect ink distribution and load equalization or balance so that substantially constant torque is maintained throughout the entire cycle of operation of the ink distributing mechanism. By maintaining substantially constant torque, vibratory impulses are reduced or eliminated, thereby preventing these impulses disturbing or effecting the ink distributing mechanism.

Having thus described my invention, what I claim as new and useful in the art, is:—

30 1. In an inking mechanism for a printing couple including a plate cylinder and an impression cylinder, a plurality of rotary ink distributing cylinders, means for supplying ink to one of the cylinders, means for axially reciprocating the ink distributing cylinders so that only one cylinder is axially stationary at a time and the reciprocatory impulses of the cylinders being equally separated so that the cylinders follow each other through similar cycles of operation 40 during equal periods of operating time, to maintain a constant balanced load on the said ink distributing cylinder reciprocating means, ink distributing rollers operably engaging the ink distributing cylinders and coacting therewith to spread the ink in a uniform film, and means for conveying the ink film to the plate cylinder.

50 2. In an inking mechanism for a printing couple including a plate cylinder and an impression cylinder, a plurality of rotary ink distributing cylinders, means for supplying ink to one of the cylinders, constantly moving means for axially reciprocating the ink distributing cylinders so that only one cylinder is axially stationary at a time and the reciprocatory impulses of the cylinders being equally separated so that the cylinders follow each other through similar cycles of operation during equal periods of operating time, ink distributing rollers operably engaging the ink distributing cylinders and coacting therewith to spread the ink in a uniform film, and means for conveying the ink film to the plate cylinder.

55 3. In an inking mechanism for a printing couple including a plate cylinder and an impression cylinder, a plurality of rotary ink distributing cylinders, means for supplying ink to one of the cylinders, rotary means for axially reciprocating the ink distributing cylinders so that only one cylinder is axially stationary at a time and the reciprocatory impulses of the cylinders being equally separated so that the cylinders follow each other through similar cycles of operation during equal periods of operating time, ink distributing rollers operably engaging the ink distributing cylinders and coacting therewith to

spread the ink in a uniform film, and means for conveying the ink film to the plate cylinder.

4. In an inking mechanism for a printing couple including a plate cylinder and an impression cylinder, a plural number greater than two and less than five of rotary ink distributing cylinders, means for supplying ink to one of the cylinders, means for axially reciprocating the ink distributing cylinders so that only one cylinder is axially stationary at a time, the reciprocatory impulses of the cylinders being equally separated so that the cylinders follow each other through similar cycles of operation during equal periods of operating time, ink distributing rollers operably engaging the ink distributing cylinders and coacting therewith to spread the ink in a uniform film, and means for conveying the film to the plate cylinder.

5. In an inking mechanism for a printing couple including a plate cylinder and an impression cylinder, a plural number greater than two and less than five of rotary ink distributing cylinders, means for supplying ink to one of the cylinders, constantly moving means for axially reciprocating the ink distributing cylinders so that only one cylinder is axially stationary at a time, the reciprocatory impulses of the cylinders being equally separated so that the cylinders follow each other through similar cycles of operation during equal periods of operating time, ink distributing rollers operably engaging the ink distributing cylinders and coacting therewith to spread the ink in a uniform film, and means for conveying the film to the plate cylinder.

6. In an inking mechanism for a printing couple including a plate cylinder and an impression cylinder, a plural number greater than two and less than five of rotary ink distributing cylinders, means for supplying ink to one of the cylinders, rotary means for axially reciprocating the ink distributing cylinders so that only one cylinder is axially stationary at a time, the reciprocatory impulses of the cylinders being equally separated so that the cylinders follow each other through similar cycles of operation during equal periods of operating time, ink distributing rollers operably engaging the ink distributing cylinders and coacting therewith to spread the ink in a uniform film, and means for conveying the film to the plate cylinder.

7. In an inking mechanism for a printing couple including a plate cylinder and an impression cylinder, a plurality of rotary ink distributing cylinders positioned in operative order relative to the printing cylinder, means for supplying ink to the ink distributing cylinder which is furthestmost from the printing cylinder, means for axially reciprocating the ink distributing cylinders so that only one is axially stationary at a time and the reciprocatory impulses of the cylinders being equally separated so that the cylinders follow each other through similar cycles of operation during equal periods of operating time, ink distributing rollers operably engaging the ink distributing cylinders and coacting therewith to spread the ink in a uniform film, and means for conveying the ink film to the plate cylinder.

8. In an inking mechanism for a printing couple including a plate cylinder and an impression cylinder, a plural number less than five of rotary ink distributing cylinders, means for supplying ink to one of the ink distributing cylinders, means for axially reciprocating the rotary ink distributing cylinders, so that more than half the number of ink distributing cylinders are constantly moving axially, the reciprocatory impulses of the cyl-

inders being equally separated so that the cylinders follow each other through similar cycles of operation during equal periods of operating time, ink distributing rollers operably engaging the ink distributing cylinders and coacting therewith to spread the ink in a uniform film, and means for conveying the ink film to the plate cylinder.

9. In an inking mechanism for a printing couple including a plate cylinder and an impression cylinder, a plural number less than five of rotary ink distributing cylinders positioned in operative order relative to the printing cylinder, means for supplying ink to the ink distributing cylinder which is furthermore operably from the printing cylinder, means for axially reciprocating the rotary ink distributing cylinders so that more than half the number of these cylinders are constantly moving axially, the reciprocatory impulses of the cylinders being equally separated so that the cylinders follow each other through similar cycles of operation during equal periods of operating time, ink distributing rollers operably engaging the ink distributing cylinders and coacting therewith to spread the ink in a uniform film, and means for conveying the ink film to the plate cylinders.

10. In an inking mechanism for a printing couple including a plate cylinder and an impression cylinder, three rotary ink distributing cylinders, means for supplying ink to one of the ink distributing cylinders, means for axially reciprocating the ink distributing cylinders one in advance of the others, ink distributing rollers operably engaging the ink distributing cylinders and coacting therewith to spread the ink in a uniform film, and means for conveying the ink film to the plate cylinder.

11. In an inking mechanism for a printing couple including a plate cylinder and an impression cylinder, three rotary ink distributing cylinders, means for supplying ink to one of the ink distributing cylinders, rotary means for imparting axial reciprocatory motion to the ink distributing cylinders, the reciprocatory impulses of the cylinders being equally separated so that the cylinders follow each other through similar cycles of operation during equal periods of operating time, ink distributing rollers operably engaging the ink distributing cylinders and coacting therewith to spread the ink in uniform film, and means for conveying the ink film to the plate cylinder.

12. In an inking mechanism for a printing couple including a plate cylinder and an impression cylinder, a plurality of rotary ink distributing cylinders, means for supplying ink to one of the ink distributing cylinders, a rotary member for imparting axial reciprocatory motion to the ink distributing cylinders so that each ink distributing cylinder receives its maximum reciprocatory impulses 120 degrees of a cycle of operation of the said rotary member in advance of the succeeding cylinder, ink distributing rollers operably engaging the ink distributing cylinders and coacting therewith to spread the ink in a uniform film, and means for conveying the ink film to the plate cylinder.

13. In an inking mechanism for a printing couple including a plate cylinder and an impression cylinder, a plurality of rotary ink distributing cylinders, means for supplying ink to one of the ink distributing cylinders, a rotary member for imparting axial reciprocatory motion to the ink distributing cylinders so that each ink distributing cylinder receives its maximum reciproc-

catory impulses 120 degrees of a cycle of operation of the said rotary member in advance of the following cylinder, ink distributing rollers operably engaging the ink distributing cylinders and coacting therewith to spread the ink in a uniform film, and means for conveying the ink film to the plate cylinder.

14. In an inking mechanism for a printing couple including a plate cylinder and an impression cylinder, a plurality of rotary ink distributing cylinders, means for supplying ink to one of the ink distributing cylinders, a rotary shaft driven from one of the cylinders of the printing couple, crank members carried by the shaft and operably positioned substantially 120 degrees apart, means for operably connecting each crank member to an ink distributing cylinder to impart reciprocatory motion thereto, ink distributing rollers operably engaging the ink distributing cylinders and coacting therewith to spread the ink in a uniform film, and means for conveying the ink film to the plate cylinder.

15. In a printing unit, two printing couples, each printing couple including a plate cylinder and an impression cylinder, a plurality of horizontally disposed ink distributing cylinders positioned in substantially vertical alinement below each plate cylinder, means for operably interconnecting the ink distributing cylinders for rotation, means for rotating the ink distributing cylinders in such directions that the portions of their peripheries which are disposed towards the center of the printing unit move upwardly, an ink rail positioned at the inner side of the vertically disposed ink distributing cylinders located below each plate cylinder to supply ink to the upwardly moving peripheral portion of the lowermost ink distributing cylinder, ink distributing rollers operably engaging the ink distributing cylinders and coacting therewith to spread the ink in a uniform film, and means for conveying the ink film to the plate cylinder.

16. In a printing unit, two printing couples, each printing couple including a plate cylinder and an impression cylinder, three horizontally disposed ink distributing cylinders positioned in substantially vertical alinement below each plate cylinder, means for operably interconnecting the ink distributing cylinders for rotation, means for rotating the ink distributing cylinders in such directions that the portions of their peripheries which are disposed towards the center of the printing unit move upwardly, an ink rail positioned at the inner side of the vertically disposed ink distributing cylinders located below each plate cylinder to supply ink to the upwardly moving peripheral portion of the lowermost ink distributing cylinder, ink distributing rollers operably engaging the ink distributing cylinders and coacting therewith to spread the ink in a uniform film, and means for conveying the ink film to the plate cylinder.

17. In an inking mechanism for a printing couple including a plate cylinder and an impression cylinder, a plurality of rotary ink distributing cylinders, means for supplying ink to the cylinders, spaced bearings, a crank shaft rotatably supported in the bearings, a plurality of cranks carried by the shaft, means for operably connecting each crank to an ink distributing cylinder so that rotation of the shaft reciprocates the cylinders axially, the cranks being so disposed that a constantly balanced load is maintained on the crank shaft bearings and no more than one ink distributing cylinder is axially sta-

tionary at a given time, ink distributing rollers operably engaging the ink distributing cylinders and coacting therewith to spread the ink in a uniform film, and means for conveying the ink film to the plate cylinder.

- 5 18. In an inking mechanism for a printing couple, including a plate cylinder and an impression cylinder, three rotary ink distributing cylinders, means for supplying ink to the cylinders, spaced axially aligned bearings, a crank shaft rotatably supported in the bearings, three radially offset cranks carried by the shaft and operably

spaced 120° apart, means for operably connecting each crank to an ink distributing cylinder so that rotation of the shaft reciprocates the cylinders axially, the operable disposition of the cranks maintaining a constantly balanced load on the crank shaft bearing, ink distributing rollers operably engaging the ink distributing cylinders and coacting therewith to spread the ink in a uniform film, and means for conveying the ink film to the plate cylinder.
